United States Patent Office.

D. WEBSTER RANKE, OF LIMESTONEVILLE, PENNSYLVANIA.

Letters Patent No. 78,828, dated June 9, 1868; antedated June 4, 1868.

GAS-GENERATOR.

The Schedule referred to in these Letters Patent and making part of the same.

TO ALL WHOM IT MAY CONCERN:

Be it known that I, D. WEBSTER RANKE, of Limestoneville, in the county of Montour, and State of Pennsylvania, have invented a new and useful Improvement in Gas-Generator; and I do hereby declare that the following is a full, clear, and exact description thereof, which will enable those skilled in the art to make and use the same, reference being had to the accompanying drawings, forming part of this specification.

This invention relates to a new and improved method of generating gas from spirits or hydrocarbon-oils; and it consists in the peculiar construction and arrangement of the retort, and in the manner in which the gas-tube or tubes are protected from the heat of the flame, as will be hereinafter described.

Figure 1 is a vertical section of the apparatus through the line x x of fig. 2, showing the retort, and the manner in which it is arranged in reference to the other parts.

Figure 2 is a view of the retort and deflector, as seen when the same are turned bottom side up. Similar letters of reference indicate corresponding parts.

A is the retort.

B is the deflector.

C is the gas-pipe.

D is the pipe which supplies the oil or liquid to the retort.

E is a protector for the gas-pipe.

The retort is formed of any suitable kind of metal, with an orifice through its centre, as seen in the drawing, so that the liquid is contained in an annular chamber, as seen.

The gas-pipe C passes up through the bottom of the retort, and extends to near its upper side, or above the liquid.

This pipe is curved, so that its inner end is brought to the centre of the retort, where the burner is attached, as seen in the drawing.

The protector E keeps the heat of the flame from the gas-tube, reflecting or radiating it to the retort.

The deflector B is provided with bearers E, which rest upon the retort, as seen in the drawing.

The supply of oil or liquid is regulated by a cock in the tube D, so that there shall always be space for the gas or vapor above it in the retort.

Having thus described my invention, I claim as new, and desire to secure by Letters Patent—

The gas-generator, constructed as described, consisting of the annular reservoir A, in the inner side of which the curved pipe C is secured, its base extending within the reservoir, above the level of the oil, and the burner upon its end extending to the central opening in the reservoir A, and provided with the protector E, the perforated deflector B, above the reservoir, and the supply-pipe D, all arranged as described for the purpose specified.

D. WEBSTER RANKE.
